(57) **CLAIM**

The ornamental design for a fifth wheel with oil grooves, as shown and described.

DESCRIPTION

FIG. 1 is a perspective view of fifth wheel with oil grooves embodying the design of the present invention;

FIG. 2 is a top view of the fifth wheel with oil grooves of FIG. 1;

FIG. 3 is a bottom view of the fifth wheel with oil grooves of FIG. 1;

FIG. 4 is a front view of the fifth wheel with oil grooves of FIG. 1;

FIG. 5 is a back view of the fifth wheel with oil grooves of FIG. 1;

FIG. 6 is a right hand view of the fifth wheel with oil grooves of FIG. 1; and,

FIG. 7 is a left hand view of the fifth wheel with oil grooves of FIG. 1.
